PLAYGROUND EQUIPMENT SUPPORT

Ronald L. Ewers, Hillsdale, Mich., assignor to Game
Time, Inc., Litchfield, Mich.

Filed Mar. 18, 1971, Ser. No. 125,903

Term of patent 14 years

Int. Cl. D21—03

U.S. Cl. D34—5

FIG. 1

FIG. 4

FIG. 1 is a right side elevational view of a playground equipment support showing my design, the left side appearing as the mirror image thereof,

FIG. 2 is a front elevational view of my design,

FIG. 3 is a rear elevational view, and

FIG. 4 is a top plan view.

I claim:

The ornamental design for a playground equipment support, substantially as shown and described.
